The ornamental design for a personal computer housing, as shown and described.

DESCRIPTION

FIG. 1 is a perspective view from the front and right of the personal computer housing of our invention in a position of being opened for use;

FIG. 2 is a perspective view from the front and right of the personal computer housing of FIG. 1 in a position of being closed;

FIG. 3 is an elevation view from the front of the personal computer housing of FIGS. 1 and 2 wherein a connector is shown and the computer is shown in a position of being fully opened;

FIG. 4 is an elevation view from the rear of the personal computer housing of FIGS. 1 through 3 in the position of FIG. 3;

FIG. 5 is a top plan view of the personal computer housing of FIGS. 1 through 4 in the positions of FIG. 3 and 4;

FIG. 6 is a bottom plan view of the personal computer housing of FIGS. 1 through 5 in the position of FIG. 3 through 5;

FIG. 7 is an elevation view from the right side of the personal computer housing of FIGS. 1 through 6 in the position of FIGS. 3 through 6; and,

FIG. 8 is an elevation view from the left side of the personal computer housing of FIGS. 1 through 7 in the position of FIGS. 3 through 7.
